H. Hickman,

Picture Nail.

NO. 91,629

Patented June 22, 1869

Witnesses:

A. W. Hungorsh

O. Henkelman

Inventor
H. Hickman,
by M. M. G.
Atty

HENRY HICKMAN, OF OMAHA, NEBRASKA.

Letters Patent No. 91,629, dated June 22, 1869.

IMPROVED PICTURE-NAIL.

The Schedule referred to in these Letters Patent and making part of the same.

To all whom it may concern:

Be it known that I, HENRY HICKMAN, of Omaha, in the county of Douglas, and State of Nebraska, have invented a new and improved Picture-Nail; and I do hereby declare that the following is a full, clear, and exact description thereof, which will enable others skilled in the art to make and use the same, reference being had to the accompanying drawing, forming part of this specification.

My invention has for its object to furnish an improvement in picture-nails, by which the cord will be securely held in such a way that the picture cannot be accidentally knocked down, and which shall at the same time hold the cord away from the wall, and be in itself ornamental; and

It consists in forming the head of the nail of some ornamental design, and in two parts hinged to each other, and so formed that the cord may be passed over the shank of the upper part, and pass out between the two parts, so as to be clamped between said parts, and securely held by the weight of the suspended picture, as hereinafter more fully-described.

A is the body of the picture-nail, which may have a screw-thread cut upon it or not, as may be desired.

The head of the nail is made in two parts, B and C. The lower part, B, is formed solid upon or is rigidly attached to the body A. The upper part, C, is hinged to the part B, as shown in the figure.

The neck of the hinged part C is formed with a groove to receive the cord, and the adjacent sides or faces of the two parts are recessed or grooved, so that the cord may pass out between them so as to hang away from the wall.

The parts B and C of the head of the picture-nail may be made of some fanciful or ornamental form, as, for instance, in the form of a dog's head resting upon his fore paws, as shown in the drawing, or in the form of a fully-opened or partially-opened flower, or any other suitable device.

Having thus described my invention,

What I claim as new, and desire to secure by Letters Patent, is—

Forming the heads of picture-nails in two parts, hinged to each other, and so formed that the cord may pass around a groove in the upper part, and be clamped between the two parts in such a way as to project at the outer ends of the two parts, substantially as herein shown and described, and for the purpose set forth.

Witnesses:

HENRY HICKMAN.

W. C. KELLOGG,
JONAS GISE.